(57) **CLAIM**

The ornamental design for a portion of an insole, as shown and described.

DESCRIPTION

FIG. 1 is a perspective view of a portion of an insole showing our new design;

FIG. 2 is a bottom view thereof;

FIG. 3 is a side view thereof;

FIG. 4 is a side view of the opposite side of FIG. 3;

FIG. 5 is a front view thereof; and,

FIG. 6 is a rear view thereof.

The broken lines in the drawings illustrate portions of an insole that form no part of the claimed design.

1 Claim, 4 Drawing Sheets

FIG. 2

FIG. 3

FIG. 4

FIG. 5

FIG. 6
